(57) **CLAIM**

The ornamental design for a tire off-shoulder, as shown and described.

DESCRIPTION

FIG. 1 is a side perspective view of a tire, showing our new off-shoulder design;

FIG. 2 is an enlarged fragmentary side perspective view thereof;

FIG. 3 is a front elevational view of a tire, showing our new off-shoulder design;

FIG. 4 is an enlarged fragmentary front view thereof; and,

FIG. 5 is a side elevational view of the left side thereof. In the drawings, the broken lines depict environmental subject matter only and form no part of the claimed design.

1 Claim, 5 Drawing Sheets
